MORRIS VICTORSOHN, OF NEW YORK, N. Y., ASSIGNOR TO VICTORSON MANUFACTURING CORPORATION, OF NEW YORK, N. Y., A CORPORATION OF NEW YORK

HANGER SUPPORT

Application filed February 11, 1928. Serial No. 253,609.

The device of the present invention is primarily intended for supporting garment hangers, although it may have a wide range of utility in the arts. It is peculiarly adapted for use in converting an ordinary suitcase or the like into a wardrobe trunk, in that it permits garment hangers to be detachably mounted in the suitcase.

An object of the invention is to provide a garment hanger supporting device of this character, which may be very cheaply and inexpensively stamped from a single piece of metal.

Another object is to provide a hanger support which may be conveniently attached to the interior of a suitcase, and which, when in position, will effectively prevent inadvertent disengagement of hangers therefrom in spite of careless handling of the suitcase.

Other objects of the invention are to provide a supporting device of this nature in which a clothes hanger with garments thereon may be very quickly mounted, and a hanger support of rugged, durable construction.

With the above noted and other objects in view, the invention consists in certain novel features of construction and combinations and arrangements of parts as will be more fully hereinafter set forth and pointed out in the claims. The invention may be more fully understood from the following description in connection with the accompanying drawings, wherein—

Fig. 1 is a perspective view showing an open suitcase equipped with my improved hanger supporting devices and showing a hanger mounted therein.

Fig. 2 is a sectional plan view on the line 2—2 of Fig. 1.

Fig. 3 is a perspective view showing one of the hanger supporting devices and the end of an adjacent hanger adapted to be mounted therein.

Fig. 4 is a plan view of the blank from which the hanger support is formed.

The construction of the hanger support may perhaps be best understood from an observation of the blank of Fig. 4, and the perspective view of Fig. 3. The blank includes

what may be termed a body portion 10 having integral with opposite sides thereof sections 11 and 12. These sections are in the nature of metallic stripes, the strip 12 being materially longer than the section 11. Both strips are adapted to be bent over at right angles to the body along the dotted lines indicated at 11a and 12a in Fig. 4. The ends of the strip 12 project laterally a considerable distance beyond the body 10, and the ends of the strip 11 are defined by slits 13 entering the body 10 at right angles to the bending lines 11a and 12. These slits 13 not only define the ends of the bendable strip 11, but also partially define the outline of ears 14 integral with the ends of the body.

In the bending operation, the strips 11 and 12 are bent along the lines 11a and 12a respectively until they lie in parallel spaced relationship as seen in Fig. 3. One end 12b of the strip 12 may then be curved around until it abuts the end of the strip 11. The other end 12c of the strip 12 is preferably bent only part of the way around, leaving an opening at 15 between the adjacent end of the strip 11 and the end of the extension 12c.

With the blank bent into this formation, it will be seen that there is provided an open sided pocket, the top of which is defined by the strip 11, the bottom by the strip 12. One end of the pocket is closed by the extension 12b, and the other end of the pocket is substantially closed by the strip 12c, this member however, being raised above the top of the pocket to provide the opening 15, and to serve as a guide member, so that a hanger trunnion 16 slid rearwardly along the top of the pocket will pass through the opening 15 into the pocket.

The rear wall of the pocket is of course defined by the relatively shallow body 10 and integral with this rear wall are the upstanding lugs or ears 14 preferably apertured as at 16 for the reception of rivets, screws or other suitable securing devices.

In use, a pair of the hanger supporting devices are arranged as shown in Fig. 1. Here, a suitcase including a body 17 and hinged cover 18 is shown standing on end with two

of the hanger devices secured to the front and rear walls of the body adjacent one end thereof, so that the suitcase may serve in effect as a wardrobe trunk when a clothes hanger 19 is mounted in the hanger supports.

The hanger 19 may be of any convenient or conventional construction, and the trunnions 16 may be applied thereto in any suitable manner. One cheap method of forming the trunnions is to simply flatten one end of a short length of wire as at 20 and rivet this flattened end as at 21 to the hanger 19, leaving the unflattened projecting end 16 of the wire to constitute the trunnion or supporting arm for the hanger.

In Fig. 1 I have shown a single hanger in position between two of my improved supporting devices, while in Fig. 2 I have illustrated a pair of hangers in position. It will be obvious that the hangers are held against accidental loss or displacement, particularly when garments are mounted thereon, since the garments themselves tend to restrict movement of the hangers, and the shape of the hanger supporting devices makes it extremely difficult for a hanger to work its way out of the pockets.

It will be obvious that if desired the strip extension 12b might be left open in the same manner that the extension 12c is left open. It will also be apparent that if desired both strip ends could be closed and a slot cut in the upper strip 11 to permit the dropping of a trunnion into place.

Various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claims.

I claim:

1. A hanger support formed of a metal blank and comprising an elongated pocket member open at one side, extensions integral with the rear wall of the pocket member for anchoring the same to a support, and said member having an opening in its top through which the trunnions of garment hangers may be dropped into the pocket.

2. A hanger support formed of a metal blank and comprising an elongated pocket member open at one side, extensions integral with the rear wall of the pocket member for anchoring the same to a support, said member having an opening in its top through which the trunnions of garment hangers may be dropped into the pocket, the top and bottom of the pocket being formed by strips integral with the rear wall of the pocket and bent over into spaced substantially parallel relationship.

3. A hanger support formed of a metal blank and comprising an elongated pocket

member open at one side, extensions integral with the rear wall of the pocket member for anchoring the same to a support, said member having an opening in its top through which the trunnions of garment hangers may be dropped into the pocket, the top and bottom of the pocket being formed by strips integral with the rear wall of the pocket and bent over into spaced substantially parallel relationship, the lower strip being longer than the upper one and having its ends bent upwardly to define the end walls of the pocket.

4. A hanger support formed of a metal blank and comprising an elongated pocket member open at one side, extensions integral with the rear wall of the pocket member for anchoring the same to a support, said member having an opening in its top through which the trunnions of garment hangers may be dropped into the pocket, the top and bottom of the pocket being formed by strips integral with the rear wall of the pocket and bent over into spaced substantially parallel relationship, the lower strip being longer than the upper one and having its ends bent upwardly to define the end walls of the pocket, one of said ends abutting the end of the upper strip, the other of said ends extending above and being spaced from the upper strip to define said opening.

5. A device adapted to support one trunnion of a trunnioned garment hanger, said device comprising an attaching portion for attaching the device to a suitcase wall or the like, an elongated retainer and guide integral with the attaching portion, and in which the trunnion may have movement in opposite directions, said retainer and guide having a bottom which serves as a support for the trunnion, said retainer and guide having a top which is so constructed that the trunnion may be removed therethrough after it has been brought to a predetermined position within said retainer and guide, the top of said guide having a restricted opening therein through which removal or insertion of said trunnion may be effected.

6. A hanger supporting device comprising an element having a laterally elongated hanger trunnion receiving opening, a portion of said element serving for the purpose of attaching the device, said element being provided with ends and a flat bottom portion on which the trunnion may rest in sliding contact and said element being provided with a top plate portion which is provided with an opening for receiving the trunnion therethrough.

Signed at New York city in the county of New York and State of New York this 9th day of February, A. D. 1928.

MORRIS VICTORSOHN.
